Primary Examiner — Cynthia R Underwood(74) Attorney, Agent, or Firm — Holland & Hart, LLP(57) CLAIM

We claim the ornamental design for a cranberry sauce serving container, as shown and described.

DESCRIPTION

FIG. 1 is a front perspective view of a cranberry sauce serving container showing our new design.

FIG. 2 is a top plan view of the cranberry sauce serving container.

FIG. 3 is a bottom plan view of the cranberry sauce serving container.

FIG. 4 is a front elevation view of the cranberry sauce serving container, of which the rear elevation is a mirror image thereto.

FIG. 5 is a right side elevation view of the cranberry sauce serving container, of which the left side elevation is a mirror image thereto; and,

FIG. 6 is a sectioned view of the cranberry sauce serving container taken along the plane 6-6.
